FUSED DROP-OUT CUTOUTS

David C. Hubbard and William L. Hollander,
Centralia, Mo., assignors to A. B. Chance Company,
Centralia, Mo., a corporation of Missouri

Application March 8, 1948, Serial No. 13,704

22 Claims. (Cl. 200—114)

1

The present invention relates to fused drop-out cut-outs, and is particularly concerned with automatic fuse devices of the type adapted to be used upon transmission lines for interrupting the flow of current when the current exceeds a predetermined amount, the interruption being accompanied by the melting of the fuse and the expulsion of the parts of the fuse, accompanied by the automatic mechanical opening of the circuit, after the circuit is broken, to assure the permanent breaking of the circuit until it is manually closed, and to give an indication of the condition of the circuit.

One of the objects of the invention is the provision of an improved drop-out type fuse cut-out adapted to utilize the standard universal fuse links and provided with a fuse tube, which is closed at the top and open at the bottom and so constructed that the lower contact of the fuse tube is ejected from the bottom contact of the circuit, so that the fuse tube will hang with its opening downward before and after operation, thus protecting the fiber liner of the fuse tube from all adverse weather conditions.

Another object of the invention is the provision of an improved fuse drop-out cut-out in which the actual parting of the lower contacts upon rupture of the fuse link is delayed until after the arc has been extinguished inside the fuse tube.

Another object is the provision of an improved device of the class described in which the ejector arm travels over a predetermined arc before unlatching the lower contact, so that the actual mechanical opening of the circuit will be delayed until the arc has been definitely extinguished within the fuse tube.

Another object is the provision of an improved device of the class described in which there is a wiping contact between the contacts on the fuse tube and those on the support so that the contacts may be kept in good condition and so that the wiping contact at the lower contact of the fuse tube may be used during the unlatching of the fuse tube to assist in delaying the mechanical opening of the circuit until the arc has been extinguished within the tube.

A further object of the invention is the provision of an improved drop-out fuse construction in which the jet action from the opening at the lower end of the fuse tube reacts with the upper trunnion to produce a torque that tends to swing the lower end of the fuse tube inward towards its contact to hold the lower contact in engaged position during the blast of the arc so

2

as to delay the mechanical opening until the arc has been extinguished.

Another object of the invention is the provision of an improved construction for devices 5 of the class described in the form of the resilient spring supported contacts, and the provision of stops which protect the springs during jet action to prevent the straining of the springs and to cause the forces to react in such manner that the 10 top trunnion of the fuse tube is also held in closed position during the violent jet action from the lower end of the fuse tube.

Another object of the invention is the provision of an improved ejector construction adapted 15 to pull the fuse link from the fuse tube quickly at all times even though the rupturing currents are too light to generate sufficient gases within the fiber tube to eject the link rapidly, thus assuring the extinguishment of the arc in a minimum time.

Another object of the invention is the provision of an improved fuse tube drop-out cut-out, the parts of which are protected from the weather 20 at all times and which is also adapted to be operated in a conventional way as a disconnect by permitting the manual disengagement of the upper contacts by merely pulling outward on this 25 end of the tube, leaving the tube supported by its lower contacts and indicating that it has been 30 manually operated as a disconnect.

Another object of the invention is the provision of an improved fuse construction which is adapted to be re-fused and operated in accordance 35 with conventional procedure so that the operators will already be familiar with the mode of handling the device.

Another object of the invention is the provision of an improved fuse drop-out cut-out which is "trip-free" even during the manual closing 40 of the circuit so that when the fuse tube unit is being connected with its contacts, the operator cannot force the closing of the circuit during the existence of an overload, but while the operator is swinging the upper contact into closed position 45 and holding it, the device may nevertheless open at the bottom contact automatically if a short circuit exists at that time.

Another object of the invention is the provision of an improved fuse tube unit which is provided 50 with means for guiding and diverting the molten elements and the major force of the blast which takes place on fusing, away from the operator, so as to provide limited but effective protection for the operator and particularly for his face.

55 Another object is the provision of an improved

device of the class described having a mechanism that is unaffected by accumulations of ice and which is adequately protected from such accumulations as may occur.

Another object of the invention is the provision of a device of the class described which gives a visual indication in the open position whether the device has been operated automatically indicating the existence of a fault, or whether the device has been opened manually, indicating the purposeful de-energizing of the circuit for repairs or other reasons.

Another object is the provision of an improved contact structure which is self-aligning with relation to the trunnions on the fuse tube unit, and the provision of stops and buffers to arrest the reaction that is due to the jet action and to prevent overstressing the contact springs.

Another object is the provision of an improved fuse tube unit and support therefor, which is so constructed that the forcible closing of the contacts by slamming the fuse tube into position, tends to force the ejector arm against the bottom of the fuse tube rather than to cause the arm to place additional tension on the fuse link element, thus eliminating the shocks that are imparted to the fragile fuse link in the devices of the prior art.

Another object of the invention is the provision of an improved ejector mechanism for the fuse leader in which the cable is so arranged that it does not slide over the end of the ejector lever as the lever moves, thus reducing or substantially eliminating the friction which would be caused by such a sliding action and which would resist the ejector lever operation.

Another object is the provision of improved contacts arrangements by means of which the contact fixtures on the fuse tube unit are resiliently urged into engagement with the fixed contact arms, and by means of which the contacts are self-aligning with respect to the trunnions on the fuse tube unit, and by means of which the longitudinal pressure on the fuse tube which sometimes causes bending, after a long period of time, is substantially eliminated.

Another object is the provision of improved arrangements for holding the fuse tube unit against swinging and against return of its lower end into engagement with the lower contact arm, after the fuse has blown, the lower end has been released and the fuse tube unit has swung down at its lower end into a vertical position.

Other objects and advantages will be apparent from the following description and the accompanying drawings, in which similar characters of reference indicate similar parts throughout the several views.

Referring to the three sheets of drawings accompanying this specification,

Fig. 1 is a side elevational view in partial section, showing the complete fused drop-out cut-out assembly, with the parts in the position which they assume when it has been provided with a suitable fuse and mounted in position to protect the circuit;

Fig. 2 is a fragmentary side elevational view showing a fragment of the upper contact arm with the fuse tube unit depending therefrom in the vertical position which it assumes after the fuse has blown;

Fig. 3 is a fragmentary elevational view in partial section, showing the position of the parts at the lower contact arm and the lower end of the fuse tube unit at the time when this fuse tube unit is being supported in inverted position dur-

ing its installation for attachment of its lower contact, now shown uppermost, to the lower supporting arm;

Fig. 4 is a view similar to Figure 3, showing the same parts, as the fuse tube unit is being swung from the position of Figure 3 to that of Figure 1;

Fig. 5 is a fragmentary sectional view taken on the plane of the line 5—5 of Figure 1, looking in the direction of the arrows;

Fig. 6 is a fragmentary elevational view of the lower end of the assembly, differing from Figure 1 in that the lower contact is shown in elevation with the contact arm and hood in section; and

Fig. 7 is a fragmentary elevational view of the lower contact arm and lower end of the fuse tube unit, with the parts in the position which they assume when the upper end of the fuse tube unit has been opened manually to use the device as a manual disconnect, the fuse tube unit being swung on the lower trunnions during this action.

Referring to Figure 1, 10 indicates in its entirety the fuse drop-out cut-out assembly, which preferably includes a supporting structure 11 and fuse tube unit 12 carried thereby. The supporting structure 11 may be embodied in the single insulator type shown in Figure 1 or it may be carried by two insulators in the manner shown in the prior application of David C. Hubbard, Serial No. 11,076, filed February 26, 1948, Fuse Drop-Out Cut-Outs.

The single insulator type of Figure 1 has a porcelain insulator 13, which is formed with a multiplicity of peripherally extending skirts 14 separated by grooves 15, and the insulator preferably has a reduced cylindrical portion 16 adjacent at its middle, and additional reduced cylindrical portions 17 and 18 at each end. The middle cylindrical portion 16 of the insulator is surrounded by a metal band 19, the ends of which are provided with two laterally projecting attaching flanges, having a screw bolt 22 passing through them and clamping them together.

One of the attaching flanges has a side extension 23 provided with an aperture for receiving another screw bolt 24, which passes through the attaching flange 25 of an offset bracket 26 securing it to the clamping band 19. The offset bracket 26 has its body 27 extending at right angles to the attaching flange 25 and has another attaching flange 28 extending at an obtuse angle to the body 27.

Attaching flange 28 is secured to the supporting flange 29 of a cross-arm clamping member 30 by means of a screw bolt 31. The cross-arm clamping member 30 is adapted to engage one side of a cross-arm, the other side being engaged by a clamping plate 32, and the two clamping members 30 and 32 are drawn together by longer screw bolts 33, 34 passing through suitable apertures in the cross-arm.

Thus the insulator 13 is adapted to be supported from a horizontal cross-arm in a tilted position, so that the fuse tube unit 12 will extend diagonally upward and away from the cross-arm in such manner that whenever the fuse tube unit hangs only from the upper contact arms, it hangs in a vertical position by gravity. By reason of this position of the insulator and fuse tube unit, the fuse tube unit is so supported that it may pivot upon either the upper trunnions or the lower trunnions by gravity to a position which it will retain by gravity.

The reduced cylindrical portions 17 and 18 at each end of the insulator 13 are bordered by one

of the insulator skirts 14 on one side and a radially projecting rib 35 on the other side, forming a groove for receiving the clamping bands 36 or 37 of the upper and lower contact supporting arms 38, 39. These contact supporting arms comprise elongated narrow straps of sheet metal each having a partially cylindrical portion 36 or 37, which embraces the insulator, and each having a pair of parallel laterally projecting portions 41, 42, for supporting the spring contacts.

The projecting attaching flanges 42 of the band 37 are provided with a pair of apertures for receiving the screw bolts 43 and 44, which pass through both flanges and through the supporting flange 45 of a lower contact fixture 46, having a hood or partial housing 47 for supporting the lower contact trunnions and for enclosing the ejector mechanism and contact mechanism and protecting it from rain, snow and other adverse weather conditions.

The lower fixture 46 may consist of a cast metal member provided with a relatively flat attaching flange 45, and with an aperture 48 for passing a connector bolt 49, which is apertured below its elongated head 50 for receiving a conductor that is clamped in a groove 51 by a nut on the shank of the bolt which pulls the head against the conductor.

A similar connector 49 is carried by an upwardly projecting flange 52 carried by the upper contact fixture 53. The hood 47 has parallel side walls 54, 55, Figure 5, a curved top wall 56, a flat rear wall 57 and a flat depending wall 58, Figure 1, leaving the bottom open between the side walls 54, 55, when the fixture is installed properly, as in Figure 1.

The side walls 54, 55 are provided with laterally projecting cylindrical lugs 59, 60, having threaded apertures 61 for receiving a pair of cylindrical trunnions 62, 63 (Figure 5). The trunnions are threaded at their outer ends, and engaged in the threaded bore 61 where they are secured by means of spring washers 64 and lock nuts 65.

The inner ends 66, 67 of the trunnions are spaced from each other sufficiently to pass the relatively flat flange portions of an ejector arm 68, Figure 1, which is pivotally mounted on the tube unit 12.

The hood 47 supports a leaf spring 69, which extends along the inside of its top wall 56 and which is initially spaced from the top wall, being tensioned when bent upward as shown in Figure 1. This leaf spring 69 passes through an aperture in the rear wall 57, and is secured to a horizontal flange 70 by means of a screw bolt 71. Spring 69 urges the contact portions of the fuse tube unit 12 resiliently against the trunnions 62, 63.

The fuse tube unit 12 comprises an insulating tube 72, preferably having an outer portion 73 which is adapted to resist exposure to weather, and an inner portion 74 which is adapted to resist burning by the heat generated in the melting of the fuse, these two portions being integrally cemented together to form a single tube.

At its lower end the fuse tube 72 supports the contact fixture 75, which has an upwardly open tubular member 76 for receiving the lower end of the fuse tube. The fuse tube is fixedly secured in the ferrule 76 of the lower fixture 75 by a pair of rivet pins 77 which pass through the ferrule, and are riveted therein at such a point that the rivets 77 also pass through grooves in the side of the fuse tube 72.

The fuse tube terminates at 78, inside the blast

chute 79, and is open at its lower end where it is constantly protected from the weather by hanging downward, either in the position of Figure 1 or after blowing of the fuse in the vertical position of Figure 2. The lower fixture 75 supports the integral blast chute 79, which has a pair of parallel side walls 80, a top wall 81 flush with the end 78 of the tube and a diagonally extending rear wall 82 which extends over toward the center of the tube 72, and is adapted to deflect the gases downwardly and toward the right away from the face of the operator.

The side walls 80 of the blast chute 79 each support an outwardly projecting cylindrical stud 83, which is adapted to provide the pivotal support and point of attachment of a fuse leader guard adapted to receive and hold the cable of the fuse when the fuse is blown. The fuse leader guard forms no part of the present invention, and may be substantially as shown in the prior patent of David C. Hubbard, No. 2,461,898, dated February 15, 1949.

The lower fixture 75 is formed with an integral ring 84 located on its upper side, in Figure 1, for reception of the laterally projecting operating pin of a disconnect stick upon which the fuse unit 12 is hung when it is to be installed. Lower fixture 75 also has an integral substantially cylindrical body portion 85 below the ring 84, and provided with a cylindrical bore 86 for receiving an ejector spring 87.

The ejector spring comprises a helical coil spring reacting at its right end on the end of the bore 86, and engaging at its left end the washer 88 of a suitable ejector strut 89. Ejector strut 89 comprises a stiff strut of metal, having a reduced end 90 which passes through an aperture in the metallic washer 88, and having at its other end 91 a V-groove or fork for engaging on both sides of the ejector lever 68 at its right edge. Thus the ejector spring 87 urges the ejector lever 68 toward the left, in Figure 1, by means of the strut 89.

The upper wall of the cylindrical formation 85 is extended toward the left to form a part of a roof 92, which curves upwardly under the top wall 56 of the hood to make sure that the hood overlaps and drains on the lower fixture 75 at a point where the water will not run into the mechanism.

Referring to Figure 5, the laterally projecting portion 93 of the lower fixture 75 is provided with a rectangular slot 94 open toward the left, and adapted to receive the pivot flange 95 of the ejector lever 68 which is pivoted on the rivet 96. The rivet 96, which forms the pivot for the ejector lever, also has a laterally projecting cylindrical portion 97, Figure 5, about which the cable leader 98 may be wrapped when the fuse is installed in the fuse unit 12.

Lower contact fixture 75 also has a laterally projecting cylindrical threaded stud 99 provided with a knurled thumb nut 100, which is adapted to clamp the end of the fuse leader 98 after it has been passed about the threaded stud 99.

The present fuse units 12 are adapted to receive standard fuses, each of which has a circular button at the top adapted to be clamped against an end surface on the upper fixture 101 by means of the internally threaded cap 102. The fusible portion of the fuse is located in the upper end of the tube 72, and is connected to the stranded copper wire leader cable wire 98, which extends downwardly out of the lower end of the tube 72 and out of the blast chute 79.

Fuse leader 98 passes around the end 103 of the ejector lever 68, and is located in a groove 104 in the bottom or end of ejector lever 68. From the groove 104 the leader 98 passes about the stud 97, Figure 1, Figure 5, and its end is passed about the stud 99 and clamped by the thumb nut 109. When the fuse leader is so installed, the ejector lever 68 is tensioned, that is, it is moved from the position of Figure 2 to that of Figure 1, compressing the spring 87 and causing the fuse ejector lever 68 to place a tension on the fuse leader 98.

The ejector lever 68 is pivoted in the slot 94 between the parallel portions 105 of the lower fixture 75, and ejector lever 68 has a relatively flat body flange 106 which is relatively thin but which is re-enforced by a thicker border flange 107.

The oval aperture 108 (Figure 2) in the ejector lever flange 106 is merely for convenience in machining adjacent surfaces, comprising the flat inner surface 109 and the cylindrical end surface 110 on a pair of laterally projecting guide flanges 111. These guide flanges, which are on both sides of the ejector lever 68, also have downwardly extending lips 112, with a diagonally extending face 113 for guiding the trunnions 62, 63 into proper position. The lateral thickness of the re-enforcing border flange 107 is such that it passes between the ends 66, 67 of the trunnions which are carried by the hood 41.

The laterally projecting body 93 of the lower fixture 75 has each of its side webs 105 provided with the laterally projecting curved contact members 114. These arcuate contact members have lower partially cylindrical surfaces 115 for engaging the trunnions 62, 63, against which they are urged by the spring 69 which bears on the top of the lateral extension 93 at the flange 92, Figure 1.

The side webs 105 of the lower contact fixture 75 are extended toward the left, in Figure 2, to form the curved camming surfaces 116, which engage the spring 69 in the installation of the fuse tube unit 12 and urge the fixed contacts 114 into proper engaging position with the trunnions 62, 63.

The ejector lever 68 is also preferably provided with a pair of laterally projecting hammer flanges 117, which are beveled at 118 on the lower left corner to provide a sharp edge at 119. The sharp edge 119 is so located that it is adapted to pass above the curved upper surface of each trunnion 62, 63, so that the trunnions will be struck by the beveled surfaces 118, one of which is located on each side of the ejector lever. Thus the ejector lever has a cam 118, which is forced over the fixed trunnions to lift the fuse tube unit until the overhang of contact 114 rises above the trunnions. At the same time the impact urges contact 114 off the trunnions.

Referring to the upper contact supporting arm 38, Figure 1, here the parallel attaching flanges 41 are made longer than the flanges 42 at the bottom arm 39, for the reason that the upper arm fixture 53 is shorter and it is desired to support the tube 72 substantially parallel to the insulator 13. Bolt 43 clamps the band 36 on insulator 13.

Two additional screw bolts 120 and 121 pass through both the flanges 41 adjacent their ends, and also through an attaching flange 122 of the contact arm fixture 53 to secure this fixture to the upper arm 38. The fixture 53 pivots on the bolt 121 by reason of the clearance provided by an enlarged aperture 123 in attaching flange 122

surrounding the bolt 120. This pivotal movement provides a predetermined amount of adjustment of the jaws of the upper fixture 53 to accord variations in length of the fuse tube unit 12, and still bring the upper trunnions 124 into good contact engagement with the upper fixed contacts.

The upper contact fixture 53, on arm 38, has a rearwardly extending horizontal flange 125 provided with a threaded bore for receiving screw bolt 126, which passes through the end of a leaf spring 127 and secures it to the flange 125. The other end of leaf spring 127 engages a rotatable sleeve 128 carried by a bolt 129, which is secured in apertures in the flanges 41-41.

The rotatable sleeve 128 is located between the flanges 41-41, and serves as a roller for engaging leaf spring 127 with a minimum amount of friction. The leaf spring 127 initially extends downwardly at its left end, Figure 1, but is bent upwardly by engagement with the roller 128, which gives it an initial tension and urges the upper contact fixture 53 in a clockwise direction on its pivot bolt 121.

The upper contact fixture 53 may comprise a cast metal member, and it is preferably formed with a housing having a pair of parallel side walls 130 integrally joined to a curved top wall 131, and a depending straight back wall 132, forming a hood which is open at the bottom for receiving the upper end of the fuse tube unit 12, and for protecting the contacts and upper mechanism from snow, rain and other weather conditions.

The upper contact fixture 101, on the fuse tube unit 12, has a cylindrical body 133, with a cylindrical bore for receiving the fuse tube 72 which is again secured in place by a plurality of rivet pins 134 in a manner similar to the pins 117 at the lower end. The cylindrical body 133 has a reduced cylindrical extension 135 which is threaded externally to receive the internal threads of the cap 102, which is closed at its upper end 136.

There is a bore 137 extending through the fixture 101 and registering with the bore 138 in fuse tube 72 for receiving the fuse and its leader. At the upper right corner of the cylindrical portion 133, Figure 2, the cylindrical body 133 is provided with a pair of laterally projecting cylindrical trunnions 124, and these trunnions 124 form the upper contacts carried by fuse tube unit 12.

At its lower end the cylindrical body 133 of the upper contact fixture 101 has a partially cylindrical extension 140, which carries a laterally projecting operating ring 141. This ring has an aperture 142 like the ring 84, of sufficient size to pass the head on the laterally projecting pin of a disconnect stick by means of which the fuse tube unit 12 may be manipulated.

Ring 141 is used for operating the unit as a disconnect by merely pulling out and disconnecting the upper contact, while the unit 12 pivots on the lower trunnions. Ring 141 is also used in the installation of the fuse tube unit to swing the unit upward from the position of Figure 3, through that of Figure 4 to that of Figure 1.

The parallel side walls 130 of the upper contact fixture are spaced sufficiently to receive the trunnions 124, which extend laterally from one side wall 101 to the other side wall 101. Above the trunnions 124 the side walls 101 may again have inner walls 143, which are spaced sufficient-

ly to pass the cap 102 but which terminate in lower shoulders 144 located above the trunnions 124. In other words, the side walls of fixture 53 are thickened at 143.

The lateral shoulders 144 are formed with upwardly curved shoulders 145, above the trunnion 124 in Figure 1, for retaining the trunnion 124 in the fixture 53. Trunnion engaging shoulders 144 extend upwardly and toward the right, Figure 1, and curve upwardly at 146 to provide a camming surface for engaging the trunnions 124 to cam the fixture 53 upward until the trunnions 124 pass in the hood and behind the retaining shoulders 145.

The retaining shoulders 145 constitute the fixed contacts for engaging trunnions 124. The relatively thick parallel walls 143 of fixture 53 have outwardly flaring guide surfaces 147 at the right end (Figure 1) for engaging the cap 102 and guiding it in between the walls 143. The fixture 53 has its attaching flange 122 provided with threaded bores for receiving the screw bolts 148, Figure 1, which secure the left end of the leaf spring 149 to the fixture 53.

This leaf spring extends upwardly and is formed with a hump 150 engaging the trunnions 124 and urging them against the fixed contacts 145, when the parts are in the position of Figure 1. The right end of leaf spring 149 is bent downwardly, and has its end portion 151 engaging a laterally projecting flange 152 carried by each of the side walls 130. Such a leaf spring 149, is provided on each side of the fixture 53 adjacent each side wall 130 for engaging each trunnion.

The leaf spring 149 may also be utilized for holding the blown fuse unit 12 in the vertical position of Figure 2, and for preventing it from swinging back and forth in the wind, which might accidentally result in an accidental engagement of the lower contact with the lower fixture. For this purpose the trunnions 124 may each be provided with a flat surface at 153, Figure 2, which flatly engages the spring 149, in the depending position of Figure 2, to keep the 45 fuse tube unit from swinging.

Another mode of preventing the swinging of the fuse tube unit is to provide a spring 154, Figure 2, which has a partially cylindrical portion 155 hooked over the bolt 120, and has its rear end 156 under the roller 128. From the bolt 120 this spring 154 extends diagonally downward at 157 under the depending wall 132, where it is bent upward to provide a resilient end portion 158 that engages the side of the cap, in the position of Figure 1, and engages the top of the cap in Figure 2. Thus, when the fuse is blown and the unit 12 swings down from the position of Figure 1 to that of Figure 2, the spring 154 will thereafter tend to keep it from swinging on its upper pivots.

Operation

The mode of manipulation and mode of operation of the mechanism is as follows: A fuse with its leader 98, arranged as shown in Figure 1, is first placed in the fuse tube unit 12, then ejector lever 68 being pressed up against the end of the baffle wall 82 tensions the spring, the leader passing through the groove 104 around the pin 97, and being secured by means of thumb nut 100.

A predetermined tension is thus placed upon the fuse leader 98, tending to withdraw this leader from the tube 72 as soon as the fuse melts. The explosive tendency of the melting fuse, supplemented by the leader ejector 68, tends to 75

break the circuit as quickly as possible and to extinguish the arc inside the tube 72.

The fuse tube unit 12 having been re-fused, it is then hung upon a disconnect stick by means of the ring 84, in the position of Figure 3, and then the fuse tube unit may be lifted by means of the stick until the lip 112 passes over the trunnions 62, 63, as shown in Figure 3, and the unit is hung on the trunnions 63 by means of the cylindrical portions 110 of the laterally projecting flanges 111.

It should be understood that the trunnions 62, 63 project laterally from each parallel side wall 54, 55, but terminate with a space between their ends into which the ejector lever can be inserted. The laterally projecting flanges 111 on the ejector lever project far enough to extend over the inwardly projecting trunnions carried by the side walls 55, so that the ejector lever serves at this time as a support with which to hang the fuse tube unit 12 on the lower trunnions in the inverted position of Figure 3.

The operator then removes his disconnect stick from the ring 84 and places it in the ring 141 which is the lowermost, but not shown in Figure 3. The operator then uses the disconnect stick to pivot the fuse tube unit 12 counterclockwise from the position of Figure 3, through that of Figure 4, to the position of Figure 1.

As the fuse tube unit 12 passes from the depending position of Figure 3 to the position of Figure 4, it will be seen that the laterally projecting flange 111 engages the trunnions 62 and 63 by means of its flat surface 109, Figure 4. As the fuse tube unit moves upward counterclockwise from Figure 4, it will be seen that the tendency of gravity is to cause the fuse tube unit 12 to slide toward the left on the trunnions 62, 63, due to the fact that the surface 109 will slope downward toward the left, and the trunnions 62, 63 will move into engagement with the fixed contacts 114.

When the fuse tube unit reaches the position of Figure 1 then the fixed contacts 114 engage the trunnions 62, 63, with a slight overhang of the fixed contacts 114 behind or to the left of the trunnions 62, 63, whereby the lower contacts 114 are retained in engagement with the trunnions 62, 63.

When the upper end of the fuse tube unit 12 approaches the upper contact fixture 53, the cap 102 will be guided between the side walls of the upper hood by the flaring guide surfaces 147, and the trunnions 124 will pass under the curved surface 146 and along under the shoulder 144 until the trunnions 124 engage and compress spring 149 and snap behind the curved retaining shoulder or fixed contact 145. Then the fuse unit has been installed, as shown in Figure 1.

Operation as a disconnect

To operate the assembly as a disconnect, with the parts in the position of Figure 1, the lineman may hook the end of a disconnect stick in the upper ring 141. By pulling on the disconnect stick the curved upper surface of the trunnions 124 will cam the retaining shoulder or fixture contact 145 upward, this motion being permitted by its pivotal mounting on the bolt 121, and being resisted by the spring 127.

The shape of the parts is such that the fuse tube unit 12 can be pulled out of engagement with its upper contacts and can be lowered into the position of Figure 3, pivoting on the lower trunnions 62, 63. The location of the parts in

this position, hanging from its lower trunnions, indicates to the user that the line has been purposefully opened, using the device as a disconnect.

The disconnect can be closed in the same manner as it was closed in the installation of the fuse tube unit, by swinging the fuse tube unit upward counterclockwise with the disconnect stick engaging the ring 144 until the contacts 124, 145 engage each other.

Operation as a fused drop-out cut-out

When a surge of current melts the fuse carried by the upper end of the fuse leader 98, the gases and melted parts are expelled out of the lower end of the tube 72 and are directed by the blast chute 79 away from the face of the operator. At the same time the release of the tension on the fuse leader 98 permits the ejector lever 68 to be moved by its spring in a clockwise direction, in Figure 1, to withdraw the fuse leader 98 from the tube 72 and assure the mechanical disconnection of the leader from the cap 162 by pulling the leader out of the tube 72.

In this action it is advantageous to have the leader wound about the extension 97 of the ejector lever pivot, because this involves no sliding across that point of support of the leader and thus minimizes the friction in pulling out the leader.

When the ejector lever 68 moves clockwise, on the blowing of a fuse, hammer flange 117 has its sharp end moved toward the trunnions 62, 63 until the sharp end of this hammer lever engages between the trunnion and the fixed contact 114, on each side of the lower fixture 75.

This tends to raise the contacts 114 and the entire fuse tube unit 12 sufficiently for the overhang of the contacts 114 to clear the trunnions 62, 63, and simultaneously urges the contacts 114 outwardly toward the right away from the trunnions 62, 63. The fuse tube unit tends to swing by gravity also from the position of Figure 1 to that of Figure 2, and thus as soon as the overhang of the contacts 114 on trunnions 62, 63 is released the fuse tube unit 12 tends to swing to the right, at its lower end, in a counterclockwise direction from the position of Figure 1, to that of Figure 2. When the fuse tube unit is in this position it is an indication that the circuit has not been opened by using the device as a disconnect, but it has been opened by the blowing of a fuse.

It will thus be observed that we have invented a fused drop-out cut-out in which the jet action of the expelled gases will tend to push the fuse tube unit into engagement with its upper and its lower contacts, retarding any tendencies of the device to open too quickly. The device will not open until the power arcs are extinguished, because it is only after the arc is extinguished that the jet action ceases from pressing the fuse tube unit backwardly into engagement with its contacts.

The present assembly has the contacts so arranged that they are self-aligning to compensate for discrepancies in the length of the fuse tube units or in the spacing between the contact supporting arms, which are due to the variations in manufacture. The advantages of our improved device may be summarized as follows:

1. It is adapted to use standard universal fuse links of any manufacturer and to be handled according to conventional practice.

2. The lower contact of the fuse tube is ejected

from the bottom contact arm upon rupture of the fuse link so that the fuse tube will hang with its opening extending downward after operation, thus protecting the interior of the fuse tube from all adverse weather conditions.

3. The construction of the mechanism is such that the mechanical opening of the lower contacts is delayed until the arc has been definitely extinguished.

4. The jet action from the lower end of the tube tends to keep the upper end of the fuse tube in its proper position and to hold the lower end in position until after the blast, thus delaying mechanical opening until the arc has been extinguished.

5. The resilient spring contacts with their wide flaring ends are adapted to register with the trunnions of the fuse tube units, even though the dimensions may vary due to manufacturing tolerances and the contacts may give sufficiently to become self-aligning as they engage the trunnions.

6. Any undue strain on the spring contacts is prevented by the provision of stop surfaces which take the thrust that is caused by jet action during rupture of a fuse.

7. The present fuse unit may be operated as a disconnect switch, but when so operated its automatic mechanism is still "trip-free," so that a fault on the line will open the lower contacts even while the operator is closing and holding the upper contacts.

8. The device gives a visual indication at all times whether it is actively in the circuit or whether the circuit has been broken purposefully at the top or automatically by rupture of a fuse at the bottom.

While we have illustrated a preferred embodiment of our invention, many modifications may be made without departing from the spirit of the invention, and we do not wish to be limited to the precise details of construction set forth, but desire to avail ourselves of all changes within the scope of the appended claims.

Having thus described our invention, what we claim as new and desire to secure by Letters Patent of the United States, is:

1. In a drop-out fuse cut-out, the combination of an insulating support, with an upper contact arm, a fuse tube unit and means for pivotally supporting said fuse tube unit from said upper contact arm, a lower contact arm carried by said support, a trunnion carried by said lower contact arm, a fixed contact carried by said fuse tube unit for engagement with said trunnion, a spring-biased fuse ejector lever carried by said fuse tube unit, and cam means carried by the ejector lever and adapted to engage the trunnion and lift the fuse tube unit to effect a release of the fixed contact from the trunnion when the fuse is melted releasing the ejector lever.

2. In a drop-out fuse cut-out, the combination of an insulating support, with an upper contact arm, a fuse tube unit and means for pivotally supporting said fuse tube unit from said upper contact arm, a lower contact arm carried by said support, a trunnion carried by said lower contact arm, a fixed contact carried by said fuse tube unit for engagement with said trunnion, a spring-biased fuse ejector lever carried by said fuse tube unit, and cam means carried by the ejector lever and adapted to engage the trunnion and lift the fuse tube unit to effect a release of the fixed contact from the trunnion when the fuse is melted releasing the ejector lever, said

fixed contact comprising an arcuate member engaging above the trunnion and overhanging behind the trunnion to latch the fuse tube unit to the trunnion.

3. In a drop-out fuse cut-out, the combination of an insulating support, with an upper contact arm, a fuse tube unit and means for pivotally supporting said fuse tube unit from said upper contact arm, a lower contact arm carried by said support, a trunnion carried by said lower contact arm, a fixed contact carried by said fuse tube unit for engagement with said trunnion, a spring-biased fuse ejector lever carried by said fuse tube unit, and cam means carried by the ejector lever and adapted to engage the trunnion and to effect a release of the fixed contact from the trunnion when the fuse is melted releasing the ejector lever, said fixed contact comprising an arcuate member engaging above the trunnion and overhanging behind the trunnion to latch the fuse tube unit to the trunnion and said cam means lifting said fuse tube unit until the overhang passes forwardly over the trunnion to release the fuse tube unit to swing by gravity to the open position.

4. In a drop-out fuse cut-out, the combination of an insulating support, with an upper contact arm, a fuse tube unit and means for pivotally supporting said fuse tube unit from said upper contact arm, a lower contact arm carried by said support, a trunnion carried by said lower contact arm, a fixed contact carried by said fuse tube unit for engagement with said trunnion, a spring-biased fuse ejector lever carried by said fuse tube unit and a supporting flange carried by the ejector lever, and facing upward when the fuse tube unit is installed for temporarily supporting the fuse tube unit on said trunnion, when the fuse tube unit hangs downwardly from the lower contact arm during installation or when used as a disconnect by separating the fuse tube unit from the upper contact arm.

5. In a drop-out fuse cut-out, the combination of an insulating support, with an upper contact arm, a fuse tube unit and means for pivotally supporting said fuse tube unit from said upper contact arm, a lower contact arm carried by said support, a trunnion carried by said lower contact arm, a fixed contact carried by said fuse tube unit for engagement with said trunnion, a spring-biased fuse ejector lever carried by said fuse tube unit and a supporting flange carried by the ejector lever, and facing upward when the fuse tube unit is installed for temporarily supporting the fuse tube unit on said trunnion, when the fuse tube unit hangs downwardly from the lower contact arm, said flange having a partially cylindrical formation for engaging the top of the trunnion with the fuse tube unit depending.

6. In a drop-out fuse cut-out, the combination of an insulating support, with an upper contact arm, a fuse tube unit and means for pivotally supporting said fuse tube unit from said upper contact arm, a lower contact arm carried by said support, a trunnion carried by said lower contact arm, a fixed contact carried by said fuse tube unit for engagement with said trunnion, a spring-biased fuse ejector lever carried by said fuse tube unit and a supporting flange carried by the ejector lever, and facing upward when the fuse tube unit is installed for temporarily supporting the fuse tube unit on said trunnion, when the fuse tube unit hangs downwardly from the lower contact arm, said flange having a partially cylindrical

formation for engaging the top of the trunnion with the fuse tube unit depending, and said flange having an upwardly extending guide portion for supporting the fuse tube unit on said trunnion as the fuse tube unit is swung upward, and for guiding the trunnion into engagement with said fixed contact.

7. In a drop-out fuse cut-out, a lower arm supporting structure comprising an insulating support and a transversely extending arm carried by said support, a lower contact member comprising a metal member formed with a hood having substantially parallel side walls and enclosed on its upper side between said side walls, said hood having a pair of aligned inwardly projecting cylindrical trunnions carried by said side walls for engagement with a fixed contact on the lower end of a fuse tube unit.

8. In a drop-out fuse cut-out, a lower arm supporting structure comprising an insulating support and a transversely extending arm carried by said support, a lower contact member comprising a metal member formed with a hood having substantially parallel side walls and enclosed on its upper side between said side walls, said hood having a pair of aligned inwardly projecting cylindrical trunnions carried by said side walls for engagement with a fixed contact on the lower end of a fuse tube unit, said side walls being provided with threaded bores, and said trunnions each having a threaded shank for reception in one of said bores, and locking means on said shank outside of said hood for securing said trunnions.

9. In a drop-out fuse cut-out, a lower arm supporting structure comprising an insulating support and a transversely extending arm carried by said support, a lower contact member comprising a metal member formed with a hood having substantially parallel side walls and enclosed on its upper side between said side walls, said hood having a pair of aligned inwardly projecting cylindrical trunnions carried by said side walls for engagement with a fixed contact on the lower end of a fuse tube unit, said hood also supporting a leaf spring extending from its top rear side across a curved portion of its top to permit bowing of the leaf spring toward said curved portion, and for engaging a fuse tube unit contact fixture and urging a fixed contact into engagement with said trunnions.

10. In a fuse drop-out cut-out, the combination of an insulating support, with a pair of contact supporting arms carried by said support, a hooded upper contact structure carried by the upper of said arms, a fuse tube unit having means at its upper end for pivotal and latching engagement with said upper contact structure, a lower contact structure carried by the lower of said contact arms, a fuse ejector lever pivotally mounted on said fuse tube unit, a fixed contact mounted on the lower end of said fuse tube unit and adapted to have latching engagement with the lower contact structure on said arm, and means actuated by said fuse ejector lever for releasing said latching engagement whereby the blowing of the fuse effects a release of the lower end of the fuse tube unit from said support to pivot to vertical position on its upper end, said lower contact also having a pivotal engagement whereby the upper contacts may be disconnected, the fuse tube unit pivoting on its lower contacts to serve as a manual disconnect, said lower contact on said fuse tube unit comprising an arcuate contact member bearing against a trunnion carried by

the lower arm, and having an overhang behind said trunnion to latch said contact to said trunnion.

11. In a fuse drop-out cut-out, the combination of an insulating support, with a pair of contact supporting arms carried by said support, a hooded upper contact structure carried by the upper of said arms, a fuse tube unit having means at its upper end for pivotal and latching engagement with said upper contact structure, a lower contact structure carried by the lower of said contact arms, a fuse ejector lever pivotally mounted on said fuse tube unit, a fixed contact mounted on the lower end of said fuse tube unit and adapted to have latching engagement with the lower contact structure on said arm, and means actuated by said fuse ejector lever for releasing said latching engagement whereby the blowing of the fuse effects a release of the lower end of the fuse tube unit from said support to pivot to vertical position on its upper end, said lower contact also having a pivotal engagement whereby the upper contacts may be disconnected, the fuse tube unit pivoting on its lower contacts to serve as a manual disconnect, said lower contact on said fuse tube unit comprising an arcuate contact member bearing against a trunnion carried by the lower arm, and having an overhang behind said trunnion to latch said contact to said trunnion, said fuse ejector lever being spring-biased, and said means comprising a lifting hammer carried by said ejector lever for engaging the trunnion on said support for raising the fuse tube unit and the contact with its overhang sufficiently to pass over said trunnion to release said arcuate contact from said trunnion when the fuse melts.

12. In a drop-out fuse cut-out, the combination of an insulating support, with a fuse tube unit, and latching means for pivotally mounting the upper end of the fuse tube unit on said support, latching means for pivotally securing the lower end of the fuse tube unit to said support, said fuse tube unit being closed at its upper end and open at its lower end, and having blast deflecting means at its lower end so directed that the jet action urges both the upper and the lower latching means toward the latched position, whereby the ejection of gases tends to keep the fuse tube unit latched in mechanical contact until the arc is broken.

13. In a drop-out fuse cut-out, the combination of an insulating support, with a fuse tube unit, and latching means for pivotally mounting the upper end of the fuse tube unit on said support, latching means for pivotally securing the lower end of the fuse tube unit to said support, said fuse tube unit being closed at its upper end and open at its lower end, and having blast deflecting means at its lower end so directed that the jet action urges both the upper and the lower latching means toward the latched position, whereby the ejection of gases tends to keep the fuse tube unit latched in mechanical contact until the arc is broken, and means carried by the fuse tube unit for effecting a release of the lower end of the fuse tube unit from said support to effect a mechanical disconnection after the arc has been broken and the blast of gases has substantially been completed.

14. In a drop-out fuse cut-out, the combination of an insulating support having an upper and a lower laterally projecting contact arm extending substantially in the same direction at an angle to the vertical, said upper contact arm being pro-

vided with a bottom open and front open hood, said hood being provided with relatively thick parallel side walls formed at their lower edges with a partially cylindrical shoulder engaging and holding trunnions, and having depending relatively thinner parallel side walls engaging and guiding the ends of said trunnions, spring means carried by said hood adjacent each thin side wall and located to urge said trunnions against said partially cylindrical shoulder, and a fuse unit comprising an insulating tube and upper and lower contact fixtures carried thereby and joined by a fuse in said tube, said upper fixture having a pair of laterally projecting aligned cylindrical trunnions receivable between said thin side walls and engaging the shoulder of said thick side walls for pivotal movement on said trunnions in a predetermined plane, the lower contact fixture also having means for pivotal engagement with the lower contact arm so that the fuse tube unit may be pivoted on the lower contact arm into and out of engagement with the upper contact arm as a disconnect.

15. In a drop-out fuse cut-out, the combination of an insulating support having an upper and a lower laterally projecting contact arm extending substantially in the same direction at an angle to the vertical, said upper contact arm being provided with a bottom open and front open hood, said hood being provided with relatively thick parallel side walls formed at their lower edges with a partially cylindrical shoulder engaging and holding trunnions, and having depending relatively thinner parallel side walls engaging and guiding the ends of said trunnions, spring means carried by said hood adjacent each thin side wall and located to urge said trunnions against said partially cylindrical shoulder, and a fuse unit comprising an insulating tube and upper and lower contact fixtures carried thereby and joined by a fuse in said tube, said upper fixture having a pair of laterally projecting aligned cylindrical trunnions receivable between said thin side walls and engaging the shoulder of said thick side walls for pivotal movement on said trunnions in a predetermined plane, the lower contact fixture also having means for pivotal engagement with the lower contact arm so that the fuse tube unit may be pivoted on the lower contact arm into and out of engagement with the upper contact arm as a disconnect, grooved supporting shoulders carried by the lower contact fixture for resting upon complementary supporting members on the lower contact arm, and means responsive to the blowing of said fuse for lifting said lower contact fixture off said supporting members, the fuse tube unit pivoting by gravity on its upper trunnions to a vertical position.

16. In a drop-out fuse cut-out, the combination of an insulating support having an upper and a lower laterally projecting contact arm extending substantially in the same direction at an angle to the vertical, said upper contact arm being provided with a bottom open and front open hood, said hood being provided with relatively thick parallel side walls formed at their lower edges with a partially cylindrical shoulder engaging and holding trunnions, and having depending relatively thinner parallel side walls engaging and guiding the ends of said trunnions, spring means carried by said hood adjacent each thin side wall and located to urge said trunnions against said partially cylindrical shoulder, and a fuse unit comprising an insulating tube and upper and lower contact fixtures carried thereby and joined by

a fuse in said tube, said upper fixture having a pair of laterally projecting aligned cylindrical trunnions receivable between said thin side walls and engaging the shoulder of said thick side walls for pivotal movement on said trunnions in a predetermined plane, the lower contact fixture also having means for pivotal engagement with the lower contact arm so that the fuse tube unit may be pivoted on the lower contact arm into and out of engagement with the upper contact arm as a disconnect, grooved supporting shoulders carried by the lower contact fixture for resting upon complementary supporting members on the lower contact arm, and means responsive to the blowing of said fuse for lifting said lower contact fixture off said supporting members, the fuse tube unit pivoting by gravity on its upper trunnions to a vertical position, said fuse tube being open at its lower end and being provided with a blast chute which is open forwardly and downwardly to direct the gases away from an operator.

17. In a drop-out fuse cut-out, the combination of an insulating support having an upper and a lower laterally projecting contact arm extending substantially in the same direction at an angle to the vertical, said upper contact arm being provided with a bottom open and front open hood, said hood being provided with relatively thick parallel side walls formed at their lower edges with a partially cylindrical shoulder engaging and holding trunnions, and having depending relatively thinner parallel side walls engaging and guiding the ends of said trunnions, spring means carried by said hood adjacent each thin side wall and located to urge said trunnions against said partially cylindrical shoulder, and a fuse unit comprising an insulating tube and upper and lower contact fixtures carried thereby and joined by a fuse in said tube, said upper fixture having a pair of laterally projecting aligned cylindrical trunnions receivable between said thin side walls and engaging the shoulder of said thick side walls for pivotal movement on said trunnions in a predetermined plane, the lower contact fixture also having means for pivotal engagement with the lower contact arm so that the fuse tube unit may be pivoted on the lower contact arm into and out of engagement with the upper contact arm as a disconnect, grooved supporting shoulders carried by the lower contact fixture for resting upon complementary supporting members on the lower contact arm, and means responsive to the blowing of said fuse for lifting said lower contact fixture off said supporting members, the fuse tube unit pivoting by gravity on its upper trunnions to a vertical position, said fuse tube being open at its lower end and having its upper trunnions located outwardly of the axis of the fuse tube so that the jet action of the gases expelled from the lower end of the tube tends to pivot the fuse tube unit toward engagement with the lower contact arm to delay interruption of the circuit at said contact arm until after expulsion of the gases.

18. In a drop-out fuse cut-out, the combination of an insulating support having an upper and a lower laterally projecting contact arm extending substantially in the same direction at an angle to the vertical, said upper contact arm being provided with a bottom open and front open hood, said hood being provided with relatively thick parallel side walls formed at their lower edges with a partially cylindrical shoulder engaging and holding trunnions, and having depending relatively thinner parallel side walls en-

gaging and guiding the ends of said trunnions, spring means carried by said hood adjacent each thin side wall and located to urge said trunnions against said partially cylindrical shoulder, and a fuse unit comprising an insulating tube and upper and lower contact fixtures carried thereby and joined by a fuse in said tube, said upper fixture having a pair of laterally projecting aligned cylindrical trunnions receivable between said thin side walls and engaging the shoulder of said thick side walls for pivotal movement on said trunnions in a predetermined plane, the lower contact fixture also having means for pivotal engagement with the lower contact arm so that the fuse tube unit may be pivoted on the lower contact arm into and out of engagement with the upper contact arm as a disconnect, grooved supporting shoulders carried by the lower contact fixture for resting upon complementary supporting members on the lower contact arm, and means responsive to the blowing of said fuse for lifting said lower contact fixture off said supporting members, the fuse tube unit pivoting by gravity on its upper trunnions to a vertical position, said upper hood being pivotally mounted on said upper contact arm and spring urged toward the lower contact arm to provide a limited upward movement of the hood and fuse tube unit.

19. In a fused drop-out cut-out, the combination of an insulating support with a pair of laterally projecting contact arms carried thereby and extending at an angle to the vertical, a fuse tube unit comprising an insulating tube and a contact fixture carried by each end of said tube and connected by a fuse in the tube, the upper of said contact fixtures being pivotally mounted on the upper contact arm, the lower of said contact fixtures being provided with a rearwardly projecting part having a pair of partially cylindrical laterally projecting supporting shoulders, a hood carried by said lower contact arm and having parallel side walls provided with a pair of aligned inwardly projecting cylindrical trunnions, said shoulders resting on said trunnions and said fuse tube unit being releasable by lifting the fuse tube unit until its partially cylindrical shoulders clear the trunnions for pivotal movement forwardly of the fuse tube unit on the upper contact arm.

20. In a fused drop-out cut-out, the combination of an insulating support with a pair of laterally projecting contact arms carried thereby and extending at an angle to the vertical, a fuse tube unit comprising an insulating tube and a contact fixture carried by each end of said tube and connected by a fuse in the tube, the upper of said contact fixtures being pivotally mounted on the upper contact arm, the lower of said contact fixtures being provided with a rearwardly projecting part having a pair of partially cylindrical laterally projecting supporting shoulders, a hood carried by said lower contact arm and having parallel side walls provided with a pair of aligned inwardly projecting cylindrical trunnions, said shoulders resting on said trunnions and said fuse tube unit being releasable by lifting the fuse tube unit until its partially cylindrical shoulders clear the trunnions for pivotal movement forwardly of the fuse tube unit on the upper contact arm, said fuse tube unit being provided with a spring pressed pivoted member for tensioning the fuse and said member having an anvil located to engage between the shoulders and the trunnions upon blowing of the fuse to lift the lower contact fixture off said trunnions.

75 21. In a fused drop-out cut-out, the combina-

tion of an insulating support with a pair of laterally projecting contact arms carried thereby and extending at an angle to the vertical, a fuse tube unit comprising an insulating tube and a contact fixture carried by each end of said tube and connected by a fuse in the tube, the upper of said contact fixtures being pivotally mounted on the upper contact arm, the lower of said contact fixtures being provided with a rearwardly projecting part having a pair of partially cylindrical laterally projecting supporting shoulders, a hood carried by said lower contact arm and having parallel side walls provided with a pair of aligned inwardly projecting cylindrical trunnions, said shoulders resting on said trunnions and said fuse tube unit being releasable by lifting the fuse tube unit until its partially cylindrical shoulders clear the trunnions for pivotal movement forwardly of the fuse tube unit on the upper contact arm, said fuse tube unit being provided with a spring pressed pivoted member for tensioning the fuse and said member having an anvil located to engage between the shoulders and the trunnions upon blowing of the fuse to lift the lower contact fixture off said trunnions, said anvil having a rearwardly extending knife portion directed to the point between the said shoulders and trunnions, the said pivoted member having means for attachment of an extension carried by the fuse located substantially at the axis of pivot of said member.

22. In a fused drop-out-cut-out, the combination of an insulating support with a pair of laterally projecting contact arms carried thereby and extending at an angle to the vertical, a fuse tube unit comprising an insulating tube and a contact fixture carried by each end of said tube and connected by a fuse in the tube, the upper of said contact fixtures being pivotally mounted on the upper contact arm, the lower of said contact fixtures being provided with a rearwardly projecting part having a pair of partially cylindrical later-

ally projecting supporting shoulders, a hood carried by said lower contact arm and having parallel side walls provided with a pair of aligned inwardly projecting cylindrical trunnions, said shoulders resting on said trunnions and said fuse tube unit being releasable by lifting the fuse tube unit until its partially cylindrical shoulders clear the trunnions for pivotal movement forwardly of the fuse tube unit on the upper contact arm, said fuse tube unit being provided with a spring pressed pivoted member for tensioning the fuse and said member having an anvil located to engage between the shoulders and the trunnions upon blowing of the fuse to lift the lower contact fixture off said trunnions, said anvil having a rearwardly extending knife portion directed to the point between the said shoulders and trunnions, the said pivoted member having means for attachment of an extension carried by the fuse located substantially at the axis of pivot of said member.
